TABLET

John R. Morrison, Washington, D. C.

Original application November 18, 1935, Serial No. 50,439, now Patent No. 2,166,016, dated July 11, 1939. Divided and this application June 15, 1939, Serial No. 279,357

2 Claims. (Cl. 282—22)

My invention relates to improvements in tablets for making an original and two carbon records.

The object of my invention is to provide a tablet of this type in which an original is placed thereon and the same inserted in a typewriter or recording machine in the usual manner of making a carbon record and in which both the original and the two record sheets can be corrected in the usual manner without removing them from the typewriter.

Another object of my invention is to provide a tablet of this character in which the original and the two record sheets may be simultaneously removed, leaving the two sheets of carbon in operative position for the placement of another original sheet thereon to be again placed in the typewriter and another original and two record sheets made, this being repeated until the entire tablet is used up.

A further object of my invention is to provide a tablet of this type in which the original and two record sheets may be gripped between the fingers on one hand while the tablet is held by the other hand and removed without touching or in any way handling the carbon sheets.

A still further object of my invention is to provide a simple, cheap and effective tablet of this character, having certain details of structure and combination of parts hereinafter more fully set forth.

In the accompanying drawing:

Figure 1 is a plan view of a tablet embodying my invention;

Figure 2 is an enlarged vertical sectional view of Figure 1.

This is a division of my application filed November 18, 1935, Serial No. 50,439, Patent No. 2,166,016, dated July 11, 1939.

Referring now to the drawing, 1 represents the tablet which is made up of any desired number of record sheets, it being understood that I am more or less limited to the number of sheets in a tablet as only a limited thickness of paper is capable of being fed into a typewriter, and, therefore, I am limited to a tablet of this thickness, although the number of record sheets may be determined by the thickness of said record sheets.

The tablet 1, as heretofore stated, is made up of a number of record sheets and for the purpose of illustration have shown four record sheets 2, 3, 4 and 5. On top of record sheet 2 is placed the sheet of carbon paper 6 and between the record sheets 3 and 5 is a second sheet of carbon paper 7. The lower ends of the record sheets 2, 3, 4

and 5 and the sheets of carbon paper 6 and 7 are arranged in stepped relation and secured together by a transverse strip 8 which is cemented thereon and necessarily cemented to each of the record sheets and the two sheets of carbon, thus forming the tablet. The record sheets 2 and 4 have their upper ends in the same plane while the record sheets 3 and 5 have their upper ends in the same plane below the upper ends of the sheets 2 and 4. The record sheets 2 and 4 are perforated at 9 and 10, while the record sheets 3 and 5 are perforated at 11 and 12, so that all of the record sheets are of the same length when severed from the tablet.

The stepped end of the tablet allows its ready insertion in the typewriter. If a mistake is made and a correction is necessary on the original and record sheets, it is made in the usual manner, as the upper end of the letterhead or original is free and likewise the carbon sheets and the two record sheets, so that the original and carbon sheets are turned back or down to give access to the record sheets so that the necessary corrections may be made.

In using the tablet, the original or letterhead with its upper end even with the upper end of the sheet 2 is placed in the typewriter. The typing is done and the tablet removed from the machine, the lower end of the tablet is gripped with one hand and the original and record sheets 2 and 4 are gripped between the thumb and forefinger of the other hand and the record sheet 2 held between the original and record sheet 4, so that the record sheets 2 and 4 are severed from the tablet, thus making two carbon record sheets. This leaves the carbon sheets 6 and 7 on record sheets 3 and 5, so that the same operation can take place, as will be readily understood.

I claim:

1. A tablet comprising a plurality of record sheets secured together at one end, every alternate sheet terminating at the same point, while the other alternate sheets terminate at a point beyond the free ends of the first-mentioned sheets, a carbon sheet secured above the uppermost record sheet and terminating above the free end of the shortest record sheet, a second carbon sheet secured between the second and third record sheets and of the same length as the first mentioned carbon sheet, each record sheet having a transverse scoring the same distance from their free ends, whereby two records are made on two sheets having their free ends terminating at the same point and being the same distance from the free ends so they may be gripped by the fin-

50
55

gers and simultaneously removed, leaving the carbon sheets above the two record sheets.

2. A manifolding tablet comprising a first series of record sheets one above the other, and having their lower ends in stepped relation, a second series of record sheets below the first series of record sheets and having their lower ends in stepped relation in the same direction as the first series of record sheets, a sheet of carbon paper between the lower record sheet of the first

series and the upper record sheet of the second series, said record sheets and sheet of carbon paper secured together in tablet form, and all of said original and record sheets having transverse scoring the same distance from the lower ends, whereby all of the original and record sheets will be of the same length when severed from the tablet. 5
